Rufus B. Fowler,

UNITED STATES PATENT OFFICE.

WILLIAM A. TURNER, OF WORCESTER, MASSACHUSETTS, ASSIGNOR TO
EDMUND CONVERSE, OF SAME PLACE.

SELF-CLOSING FAUCET.

SPECIFICATION forming part of Letters Patent No. 531,484, dated December 25, 1894.

Application filed June 28, 1890. Serial No. 367,151. (No model.)

To all whom it may concern:

Be it known that I, WILLIAM A. TURNER, a citizen of the United States, and a resident of Worcester, in the county of Worcester and State of Massachusetts, have invented a new and useful Improvement in Self-Closing Faucets, of which the following is a specification, containing a full, clear, and exact description of the same, accompanied by drawings forming a part of the same, and in which—

Figure 1 represents a sectional view of a self closing faucet embodying my invention. Fig. 2 is a sectional view of the end wall of the variable chamber and showing the adjusting screw by which the air vent to the chamber is regulated. Fig. 3 is a top view of the wires forming the cage by which the lower valve to the variable chamber is retained in place, and Fig. 4 is an end view of the adjusting screw, by which the air vent to the variable chamber is regulated.

My invention relates to that class of faucets in which the water way is automatically closed when the force employed in opening the valve has been removed, and it consists in the construction and arrangement of parts as hereinafter set forth and specifically pointed out in the subjoined claims.

A denotes the shell forming the body of the faucet.

B is a stuffing box cast integrally with the shell A and C is a partition also cast integrally with the shell A and provided with an opening C', which is surrounded with an annular valve seat C². Extending downward from one end of the partition C and integral with it is the wing C³, cutting off the upper portion of the passage through the shell A and deflecting the current of water downward so as to impart an upward motion to the water current as it flows through the opening C' in the partition C. The wing C³ is extended downward so its lower edge will come slightly below the upper edge of the cylindrical shell

E, forming an annular space between the shell E, partition C and shell C³, causing the water, which had flowed in a horizontal direction to be deflected vertically upward, so as to be carried in a direct vertical stream past the packing disk H and through the opening C', thereby preventing the current of water

carrying sand or grit from passing across the surface of the packing disk.

The shell A has a screw threaded opening D in which is screwed the cylindrical shell E open at its upper end and containing the piston E' comprising the shell F having a screw threaded opening F' in which is screwed the tubular shell G having at its lower end the outwardly projecting flange G' and at its upper end the hole G² communicating with the interior of the shell F. Between the lower end of the shell F and the flange G' are the packing rings G³ forming a water tight joint with the side wall of the cylindrical shell. The side wall of the shell F is provided with small holes F*, and within the shell F is placed the valve disk F² by which the hole G² is closed, a spring F³ pressing upon the valve disk F² to hold it down and secure the certain closing of the hole G² upon the upward movement of the piston.

A packing disk H is placed upon the upper surface of the shell F, held in place by the nut H' which is held upon the screw threaded section of the short stem H², and as the piston E' rises the disk H is brought against the annular valve seat C² closing the opening C'.

I denotes a hollow boss projecting inwardly from the end wall E² of the shell E, and having the shoulders I' upon which rests the valve disk I².

I³ is a screw held in the end wall E² and concentrically with the hollow boss I, having a V shaped slot I⁴ forming a vent hole at the side of the screw, which is enlarged or diminished as is required by withdrawing the screw or vice versa. The screw I³ is also provided with a flanged head I⁵, in order to prevent the screw from being entirely withdrawn, and above the valve disk I² are placed the crossed wires I⁶ attached to the end of the hollow boss I, in order to prevent the disk I² from being raised out of its position or being displaced.

J denotes a spiral spring within the chamber E³, with its lower end resting upon the end wall E² and with its upper end inclosed within the tubular shell G and with its tension acting to raise the piston E'.

Sliding within the stuffing box B is the spindle K having a recess K' at its lower end

to receive the valve stem H^2 . Packing rings K^2 in the box B serve to form a water tight joint around the spindle K.

K^3 denotes a screw threaded metallic ring 5 by which the rings K^2 are compressed. K^4 is a hollow screw held in the upper end of the stuffing box, and projecting a short distance above the shell A.

K^5 is a check nut upon the hollow screw K^4 10 and resting against the shell A.

Pivoted to an arm N cast integrally with the shell A is a lever handle, in which is pivoted the friction roll N^2 with its axis lying in the plane of the axis of the spindle K, so that 15 as the spindle is depressed by the pressure upon it of the friction roll N^2 the axis of the roll will move through a small arc substantially corresponding with the plane of the axis of the spindle K. By this arrangement 20 of the roll and spindle the pressure applied to the spindle will always be in a line coincident with its axis, thereby preventing any lateral pressure, which would tend to carry the spindle against the packing in the stuffing 25 box B.

The operation of my improved self-closing faucet is as follows: The valve disk H^2 is held, in its normal position, against the annular seat C^2 , thereby closing the water way through 30 the opening C' , until the spindle K is forced down by the lever handle N' , carrying the piston E' downward into the chamber E^3 and opening the water way C' . As the piston E' is forced downward, compressing the spiral 35 spring J, the valve disk I^2 will be forced down upon the shoulder I' closing the opening at the side of the screw I^3 and causing the air in the chamber E^3 to be forced out through the small openings F' , passing through the 40 hole G^2 and lifting the valve disk F^2 . When the pressure is removed from the spindle K, the tension of the spring J will force the piston E' upward closing the opening C' , and during the upward movement of the piston 45 E' the valve F^2 is closed by its own gravity, the pressure from below having been removed, aided by the spring F^3 , which renders the closing of the valve F^2 immediate and certain. The valve disk I^2 at the same 50 time is opened by the excess of atmospheric pressure from without, allowing air to flow into the chamber E^3 as the piston rises. The downward sliding motion of the spindle K and piston E' is limited by the adjusting screw 55 K^4 , which is raised or lowered as required to receive the contact of the friction roll N^2 and limit the angular motion of the lever handle N' , thereby varying the water way and consequent size of the stream. The upward movement of the piston E' is regulated by the size 60

of the vent I^4 , allowing the pressure of the atmosphere to co-operate with the tension of the spring in raising the piston and closing the opening C' . The air inclosed within the chamber E^3 also serves as a cushion to check 65 the downward movement of the piston E' , as its downward motion cannot take place faster than the flow of air through the holes F' . The recess K' is slightly larger than the diameter of the valve stem H^2 as it enters the recess in 70 order to allow for any slight variation that may occur in the alignment of the stem H^2 and the sliding spindle K. The spindle K is provided with a flange K^6 at its lower end to prevent the spindle from being pushed out 75 through the stuffing box by the water pressure. When the faucet is opened by the downward pressure upon the spindle K in the manner described, the water in flowing through the faucet passes below the wing partition C^3 80 and rises around the upper end of the piston E' flowing through the opening C' , the piston E' acting as a valve having an upward motion in a line parallel with the walls of the partition C and the wing C^3 . 85

What I claim as my invention, and desire to secure by Letters Patent, is—

1. In a faucet comprising a shell A having a partition C containing a water way, and a valve disk closing said water way, the combination of a sliding spindle by which said valve disk is actuated, a stuffing box inclosing said spindle, packing rings held in said stuffing box, a screw threaded ring K^3 by which said packing rings are compressed, spindle 90 depressing mechanism, whereby said spindle is pushed downward for the purpose of opening the valve, and a hollow screw K^4 held in the upper end of said stuffing box and in the path of said spindle depressing mechanism, 95 whereby the movement of the spindle is adjusted, substantially as described.

2. The combination of the shell A, partition C having a water way C' , shell F having one end open and carrying a valve disk by which said water way is closed, a shell G closed at one end and provided with a hole G^2 and having at its opposite end a flange G' , said shell G having its closed end screw threaded and held in the open end of said shell F and a series of packing rings G^3 between the shell F and the flange G' , substantially as described. 105 110

Dated at Worcester, in the county of Worcester and State of Massachusetts, this 24th day of June, 1890.

WILLIAM A. TURNER.
